CYLINDRICAL GRINDING MACHINE

Harold E. Balsiger, Waynesboro, Pa., assignor to
 Landis Tool Company, Waynesboro, Pa., a corporation of Pennsylvania

Application March 23, 1931, Serial No. 524,706

9 Claims. (Cl. 51—233)

This invention relates to machines for grinding plain cylindrical surfaces and particularly to a carriage traverse mechanism.

An object of the invention is to provide means for controlling movement of the work carriage to insure smooth operation at all speeds.

A further object is to provide means for maintaining a constant supply of fluid in the control means.

10 A still further object is to provide means operated by movement of the work carriage for operating the wheel feed.

Further objects and advantages will become apparent as the description proceeds.

15 Referring to the accompanying drawings, which are made a part hereof and on which similar reference characters indicate similar parts,

Figure 1 is a front elevation of the machine.

20 Figure 2, a front view of the automatic wheel feed mechanism on an enlarged scale, and

Figure 3, a diagrammatic sketch of the hydraulic mechanical and electrical lay-outs.

In the drawings reference character 10 indicates the base of a grinding machine having a work carriage 11 mounted thereon and having a wheel base 12 movable toward and from the work carriage in a well known manner. The wheel base carries a grinding wheel 13 which is

30 driven by means of an electric motor 14 through a belt 15. The work carriage has a tail stock 16 mounted at one end and a head stock 17 at the other, the headstock being driven by means of an electric motor 18. The wheel base

35 carrying the grinding wheel is fed into the work by mechanism shown in detail in Figure 2. This consists of a ratchet wheel 19 mounted on a shaft 20 which shaft is connected to any well-known gearing mechanism for moving the wheel base forward.

40 An arm 21 on the shaft 20 has a pawl 22 at its outer end engageable with the teeth on the ratchet wheel 19. Secured to or made integral with the arm 21 is an arm 23 having a gear segment cut thereon with

45 which engages gear teeth 24 on one end of a rock arm 25. The other end of the rock arm engages a spool on the outer end of a piston rod 26. The piston rod carries a piston 27 operable in a cylinder 28. Fluid lines 29 and 30 connect

50 the cylinder at opposite sides of the piston. Pressure fluid from a line 31 is delivered to lines 29 and 30 through a valve 32. The valve consists of a pair of disks against the upper of which is positioned a compression spring 33. Valve

55 stem 34 has a spool 35 thereon engaged by one

end of a lever 36. The other end of this lever carries a roller 37 which is engaged by a cam 38 attached to the work carriage 11. The work carriage may be provided with a dog at each end so as to operate the valve at each end of the stroke or if desired only a single cam may be provided on the work carriage so that the valve will be operated only at one end of the travel of the work carriage. Pressure fluid is supplied to the line 31 by a pump 39.

10 The work carriage is operated by means of hydraulic motors comprising cylinders 40 and 41 having pistons 40 and 42 movable therein. Piston rods 43 and 44 are each attached at their outer ends to the work carriage 11. The cylinders 40 and 41 are connected at the sides opposite the piston rods of each by means of a fluid line 45 in which line is positioned a control valve 46. Fluid line 31 is connected with the line 45 at each side of the valve 46 and is provided

15 with means such as check valves 47 for checking back flow from line 45. The purpose of this construction is to maintain the lines 45 constantly filled with pressure fluid so as to insure smooth operation at all times. The speed of 20 the work carriage is varied by the adjustable throttle valve 46 since fluid must flow from one side of one piston to the opposite side of the other during movement of the work carriage.

The pistons 40 and 42 are operated by fluid supplied to them by fluid lines 48 and 49. Pressure is supplied to the lines 48 and 49 from line 50 from the pump through ports 51 and 52. A valve 53 controls passage of fluid from the port

25 51 to the port 52 and a reversing valve 55 controls passage of fluid from port 52 to either of the lines 48 or 49. Pressure fluid from the 30 motors is exhausted through lines 56 and 57 to a reservoir not shown in the base of the machine.

Reversing valve 55 is operated through a valve 40 stem 58 attached to the lower end of a reversing valve shifting mechanism. The reversing lever 59 is operated by dogs 60 on the work carriage.

The lever 59 has a roller 61 on its lower end which engages cam surfaces on the top of a 45 plunger 62 for throwing the reversing lever and holding it in the thrown position in a manner well-known in machines of this type. The carriage 11 may be manually traversed by hand wheel 11' acting through any of the well known 50 traverse mechanisms.

A spring pressed relief valve 63 may be positioned between pressure line 50 and exhaust line 57. The valve 53 is connected by means of a valve stem 64 with one end of an arm 65 to the 55

other end of which is attached a valve stem 68 for operating a valve 67 which controls ports 68 and 69. When positioned to place port 68 in communication with port 69, i. e. when valve 67 is moved to the right the work carriage may be freely manually moved since fluid may freely flow from cylinder 41 without passing through throttle valve 46. For hand traverse the pressure fluid in the piston rod end of the cylinders may pass from the reversing valve through ports 52 and 78 to passage 56, from it may pass to either of the passages 48 or 49, depending on the position of the reversing valve 55. Valves 53 and 67 are operated by means of a lever 70 which has a link 71 attached to its lower end, the link being attached at its other end to the arm 65. The lever 70 has on its lower end a cam 72 which engages a roller 73, on a limit switch 74. This switch controls circuit through lines 75 to the work drive motor 18. Air bleed pipes 79 are connected to each end of cylinders 40 and 41.

In operation the lever 70 is moved to the position shown in Figure 3. Fluid from the pump 39 is delivered through line 50, port 51, port 52 and line 48 to the left of piston 80. This will move the work carriage to the right. The speed of travel, however, of the carriage will be controlled by the speed with which fluid from the cylinder 40 will flow through line 45 and needle valve 46 to the left of piston 42 in cylinder 41. When the carriage has reached its limit of travel to the right a dog on the left end of the carriage will engage reversing lever 59 and swing it to the right. This will shift reversing valve 55 so as to close line 48 and place line 49 in communication with port 52. Line 48 in the meantime may exhaust through line 56. Pressure fluid therefore passes through line 49 to the right of piston 42 to move the carriage to the left. This operation continues indefinitely with the carriage traversing back and forth past the grinding wheel. Pressure fluid from the pump 39 likewise passes through line 50, line 31 and through valve 32 to cylinder 28. When the valve 32 is in the position shown in Figure 3 pressure fluid from line 31 may pass through the line 30 to the left of piston 27. This moves piston 27 to the right and rocks the rock arm 25 counterclockwise to rotate the arm 21 clockwise to move the ratchet wheel 19 to move the grinding wheel base toward the work. As soon as the cam 38 releases the roller 37 spring 33 moves the valve 32 to close line 30 and to place line 29 in communication with line 31. Fluid then passes from pressure line 29 to the right of the piston 27 and this swings the arm 21 and the pawl 22 counterclockwise to place them in position for the next operation. When the valve 32 moves downwardly of course pressure fluid line 30 is placed in communication with exhaust line 76 and when the valve is moved in the position in which it is shown in Figure 3 line 29 is open to the exhaust. An adjusting nut 77 may be provided on the piston rod 26 to control the extent of movement of the piston rod to control the distance through which the grinding wheel is fed into the work.

It will be obvious to those skilled in the art that various changes may be made in my device without departing from the spirit of the invention and therefore I do not limit myself to what is shown in the drawings and described in the specification, but only as indicated by the appended claims.

Having thus fully described my said invention, what I claim as new and desire to secure by Letters Patent, is:

75 1. In a machine having a carriage, a hydraulic

motor for traversing said carriage comprising two cylinders, a piston in each cylinder, means connecting said motor with the said carriage, means for supplying fluid under pressure to one end of each cylinder, a closed conduit connecting the opposite ends of said cylinders with each other to permit the fluid from one cylinder to pass to the other, means for restricting the flow of fluid through said conduit, and automatic means to replace leakage from said cylinders and said conduit. 10

2. In a machine having a carriage, a hydraulic motor for traversing said carriage comprising two cylinders, a piston in each cylinder, means for supplying operating fluid to one end of each cylinder, a closed conduit connecting the opposite 15 ends of said cylinders with each other to permit the fluid from one cylinder to pass to the other, and adjustable means for restricting the flow of fluid thru said conduit.

3. In a machine having a carriage, a dual piston 20 four chamber hydraulic motor for traversing said carriage, means for supplying operating fluid to two of said chambers, a closed conduit connecting the other chambers with each other to permit the fluid to pass from one chamber to the other, 25 and adjustable means for restricting the flow of fluid thru said conduit.

4. In a machine having a carriage, a dual piston 30 four chamber hydraulic motor for traversing said carriage, means for supplying operating fluid to two of said chambers, a closed conduit connecting the other chambers with each other to permit the fluid to pass from one chamber to the other, means for restricting the flow of fluid through said conduit, and means to bypass said 35 restriction.

5. In a machine having a carriage, a dual piston 40 four chamber hydraulic motor for traversing said carriage, means for supplying operating fluid to two of said chambers, a closed conduit connecting the other chambers with each other to permit the fluid to pass from one chamber to the other, means for restricting the flow of fluid through said conduit, and means for cutting off the supply of fluid to said cylinders and for bypassing fluid around said restricting means. 45

6. In a machine having a carriage, a hydraulic 50 motor for traversing said carriage comprising two cylinders, a piston in each cylinder, piston rods connecting said pistons with said carriage, means for supplying operating fluid to one end of each cylinder, a closed conduit connecting the opposite ends of said cylinders with each other to permit the fluid from one cylinder to pass to the other, whereby said fluid opposes each of said pistons alternately to control movement of said carriage in both directions. 55

7. In a machine having a carriage, a dual piston 60 four chamber, hydraulic motor for traversing said carriage, means for supplying operating fluid to two of said chambers, a closed circuit connecting the other chambers with each other to permit fluid to pass from one chamber to the other, automatic means for replacing leakage in said conduit and the chambers connected thereto, means for restricting the flow of fluid through said conduit and means for cutting off the supply of fluid to said cylinders and for bypassing the fluid around said restricting means. 65

8. In a grinding machine, a carriage, manual means for effecting a traversing movement of said carriage, power means for effecting a traversing movement of said carriage comprising a hydraulic motor having four chambers, a source 70 75

of fluid under pressure, a reversing valve for directing said fluid under pressure to either of two of said chambers, a fluid line between the other two chambers, an adjustable valve in said line for varying the rate of movement of said carriage, means for permitting a free passage of fluid between said first two chambers, thru said reversing valve and means for permitting a free passage of fluid between said second two chambers comprising a bypass around said adjustable valve whereby to provide an unobstructed manual traverse.

9. In a grinding machine, a movable carriage, manual means for effecting a traversing move-

ment of said carriage, power means for effecting a traversing movement of said carriage comprising a fluid motor, a supply of fluid under pressure, a start and stop lever for controlling said supply and valve means operated by said lever upon shifting same to a stop position for connecting said fluid supply with an exhaust line while maintaining a connection between said supply and said motor, said valve means when in stop position providing an unobstructed passage between opposite sides of said motor to permit the manual traverse of said carriage.

HAROLD E. BALSIGER.
